PORTABLE FLUORESCENT LANTERN

Darrell J. Lowrance, Tulsa, Okla., assignor to Lowrance Electronics, Inc., Tulsa, Okla.

Filed Sept. 7, 1972, Ser. No. 286,858

Term of patent 14 years

Int. Cl. D26—02

U.S. Cl. D48—24 R

FIG. 1 is an elevational view of one side of the portable fluorescent lantern showing my new design.

FIG. 2 is a front elevational view thereof.

FIG. 3 is an elevational view of the other side thereof.

FIG. 4 is a rear elevational view thereof.

FIG. 5 is a top view thereof.

FIG. 6 is a bottom view thereof.

I claim:

The ornamental design for a portable fluorescent lantern, substantially as shown.
